(57) **CLAIM**

The ornamental design for stand for electronic devices, as shown and described.

DESCRIPTION

FIG. 1 is a perspective view of a stand for electronic devices showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof in a closed state; and, FIG. 9 is an enlarged view of portion A shown in FIG. 8. The broken lines depict portions of the stand for electronic devices and form no part of the claimed design.
